CARTRIDGE FIRING ATTACHMENT FOR
AIR RIFLES

Ralph Hilliard Dixon, Belleville, N. J.

Application March 12, 1948, Serial No. 14,488

9 Claims. (Cl. 42—1)

1

This invention relates to a device for converting an air rifle into a firearm for firing explosive cartridges.

The invention has for an object to provide a novel attachment for application to the free end portion of the barrel of an air rifle, whereby to adapt such type of rifle for the firing and discharge of explosive cartridges.

The invention has for another object to provide an attachment for the stated purpose, the cartridge holding and discharging portion of which is capable, without necessity for removal of the attachment from the air rifle barrel, of being displaced at will from its operative aligned relation to the air rifle barrel, so that the air rifle may be used in normal manner for discharge of air impelled missiles or shots.

The invention has for a further object to provide an attachment for the stated purposes which is provided with a rotatable cylinder adapted to contain a plurality of explosive cartridges, whereby rotation of the cylinder will successively bring the cartridges into position to be fired and discharged.

Other objects of the invention, not at this time more particularly enumerated, will be understood from the following detailed description of the same.

An illustrative embodiment of the invention is shown in the accompanying drawings, in which:

Fig. 1 is a side elevational view of the cartridge firing attachment of this invention as applied to the barrel of an air rifle in position for use; Fig. 2 is a top plan view of the same; Fig. 3 is a longitudinal sectional view of the same, with the air rifle barrel shown in part section and in part side elevation; Fig. 4 is a transverse sectional view, taken on line 4—4 in Fig. 1; Fig. 5 is a transverse sectional view, taken on line 5—5 in Fig. 3; and Fig. 6 is a side elevational view, showing the operative part of the cartridge firing attachment displaced from operative aligned relation to the air rifle barrel, whereby to permit normal use of the air rifle.

Similar characters of reference are employed in the hereinabove described views, to indicate corresponding parts.

Referring to the drawings, the reference character 10 indicates the free end portion of the barrel of any well known type of air rifle which is adapted to discharge small missiles, such e. g. as BB shot, by the released pressure of air which is compressed by suitably manipulated mechanism (not shown) with which air rifles are provided.

5 The cartridge firing attachment of this invention comprises a base member 11 which is provided at its rear end portion with an upstanding clamping means unitary therewith, which is 10 adapted to embrace the air rifle barrel 10, so as to clamp the base member thereto for forward extension beneath said barrel 10. The clamping means may be of any suitable specific design or form, but as illustratively shown, comprises a 15 pillow block 12 and a cooperative separable clamping cap 13. The pillow block 12 is provided in its upper face with a seating channel 14 which is shaped to conform to the under side of the air rifle barrel 10. The clamping cap 13 is also 20 formed to provide a seating channel 15 in its lower face which is shaped to conform to the upper side of said air rifle barrel 10. The pillow block 12 and clamping cap 13 are respectively provided along their meeting side marginal portions with opposed laterally extending flanges 16 and 17, through which fastening elements, such e. g. as the screws 18, may be engaged, whereby to draw down the clamping cap toward the pillow block, and thus firmly grip the interposed 25 portion of the air rifle barrel 10.

Hingedly connected, by a transverse hinge member 19, with the forward end of the base member 11, is the breech member 20 of the cartridge firing attachment. Said breech member 30 is thus connected by its lower rearward end to the base member 11, so as to be capable of down swinging movement relative to the latter. Unitary with the breech member 20, so as to extend forwardly from the upper end portion thereof, is a cartridge bullet discharge barrel 21. The breech member 20 is provided with a downwardly open cylinder chamber 22. Rotatably mounted in the cylinder chamber 22, eccentric to the bore 23 of the cartridge bullet discharge barrel 21, is 35 a cartridge supporting cylinder 24. Said cylinder 24 is provided with a plurality of chambers 25 for the reception of explosive cartridges 26. The cylinder 24 is rotatably mounted upon an axle pin 27 which is removably supported by and between the front and back walls 28 and 29 of the breech member 20. Said axle pin 27 is provided at its outer end with a finger piece 30 by which it can be manipulated. The cylinder 24 is so disposed relative to the cartridge bullet discharge 40 barrel 21 that its chambers 25, and the cartridges 26 contained therein, can be successively brought into alignment with the bore 23 of said barrel 21 when rotative movement is imparted to said cylinder. The cylinder 24 is exposed at the open 45 bottom of the cylinder 22, so as to be engageable 50 55

by a finger or thumb, inserted through said open bottom, for imparting desired rotative movement thereto. Yieldable detent means is provided for releasably holding the cylinder 24 stationary with a selected chamber 25 thereof and its contained cartridge 26 operatively aligned with the bore 23 of the cartridge bullet discharge barrel 21. In an illustrative form thereof said detent means comprises a leaf spring 31, the lower end of which is affixed, as by the fastening screw 32, to the outer face of the front wall 28 of the breech member 20. Carried by the upper free end portion of said leaf spring is a detent pin 33, which extends through an opening 34 in the front wall 28 of the breech member, so that its free end can selectively and releasably engage detent sockets 35 which are provided in the adjacent end of the cylinder 24. Said sockets 35 correspond in number and relative positions to the number and relative positions of the cylinder chambers 25. Provided in the back wall 29 of the breech member 20, so as to be aligned with the axis of the bore 23 of the cartridge bullet discharge barrel 21, and with a cylinder chamber 25 and its contained cartridge 26 which is opposed to said barrel bore 23, is a touch hole 36.

Means is provided for releasably holding the breech member 20 and cartridge bullet discharge barrel 21 upswung to operative position with said bullet discharge barrel 21 disposed in axial alignment with the bore of the air rifle barrel 10 upon which the cartridge firing attachment is operatively mounted. Illustrative of one of various possible forms of such releasable holding means, the holding means, as shown, comprises a substantially U-shaped member or bail 37, the ends of the legs of which are respectively affixed to opposite sides of the breech member 20, so that the retainer member or bail extends rearwardly therefrom, with its closed free end 38 adapted to overlap the clamping means by which the cartridge firing attachment is mounted on the air rifle barrel 10. Said closed end 38 of the retainer member or bail 37 is adapted to be releasably snapped over an anchor lug 39 with which the clamping cap 13 of the clamping means is provided. When so engaged with the anchor lug 39, the retainer member or bail 37 supports the breech member 20 and cartridge bullet discharge barrel 21 in up raised operative relation to the barrel 10 of the air rifle.

When mounting the cartridge firing attachment of this invention upon the barrel 10 of an air rifle, the former is clamped to the barrel 10 in such relation to the free extremity of the latter that the breech member 20 of the attachment will be disposed in abutted or somewhat forwardly spaced relation to said barrel extremity, when said breech member is upswung and secured in raised operative position, as shown in Figs. 1 to 3 inclusive. Under these circumstances, the touch hole 36 of the breech member 20 will be opposed to and aligned with the bore of the air rifle barrel 10. By rotating the cylinder 24, a selected chamber 25 thereof, and its contained cartridge 26, can be aligned between the bore of the air rifle barrel 10 and the bore 23 of the cartridge bullet discharge barrel 21. With the attachment thus operatively positioned, the air rifle is converted into an explosive cartridge firing rifle, and is ready to be fired as such. To fire the rifle, as thus converted, the air rifle barrel 10 is supplied with a shot 40, whereupon the air compression mechanism of the rifle is set subject to trigger release in the well known manner, where-

by to discharge air under pressure behind the shot 40, and thereby forcefully impel the latter outwardly through the barrel 10. The thus driven shot 40 will be projected through the touch hole 36 so as to make firing impact upon the cartridge 26 which is aligned with the latter, thereby exploding the cartridge powder charge with resultant discharge of the cartridge bullet through and from the discharge barrel 21 of the attachment. After one cartridge is thus fired, the cylinder 24 can be turned to bring a succeeding cartridge into firing position. If the air rifle is of the muzzle loading, single shot type, and the breech member is disposed to abut the extremity of the barrel 10, by upturning the air rifle barrel 10, the shot 40 can be returned to initial position within the air rifle barrel ready for a repetition of the above described cartridge firing operations. The cartridge firing operations can be repeated until the cartridge content of the cylinder 24 is exhausted. If the breech member is disposed in spaced relation to the extremity of the barrel 10, the used shot 40 is allowed to fall away through the intervening gap. Such spaced disposition of the breech member from the extremity of the barrel 10 will be found most convenient and preferable when the attachment is applied to an air rifle of the repeating type.

After the cartridges contained in the cylinder 24 have been discharged, said cylinder can be removed from the breech member 20, and the empty cartridge shells withdrawn therefrom, whereafter the cylinder can be reloaded and remounted in the breech member 20. To release the cylinder 24 from the breech member, the axle pin 27 is withdrawn from these parts, and the detent pin 33 relaxed, so that the cylinder can be dropped out through the open bottom of the breech member. After the cylinder 24 has been reloaded, it can be returned into the breech member and into engagement with the detent pin 33, whereafter the axle pin 27 is replaced, thus reloading the attachment ready for further cartridge firing use.

The breech member 20 with the cartridge bullet discharge barrel 21 may be displaced from operative cartridge firing relation to the air rifle barrel 10 by releasing the bail 37 from the anchor lug 39, and then swinging down the breech member 20 and barrel 21 about the hinge connection 19 (see Fig. 6). When thus downswung, the breech member 20 and barrel 21 will hang from the base member 11 below the level of the air rifle barrel 10, thus leaving the discharge end of the latter unobstructed, so that the air rifle may thereupon be used in a normal manner for discharge of air impelled missiles or shots. It will be obvious that such displacement of the breech member 20 and barrel 21 may be made without necessity for removing the attachment from its clamped relation to the air rifle barrel 10.

I am aware that various changes could be made in the above described constructions without departing from the scope of this invention as defined by the here following claims. It is therefore intended that the matter contained in the above description and shown in the accompanying drawings shall be interpreted as illustrative and not in a limiting sense.

70 I claim:

71. A cartridge firing attachment for an air rifle comprising a breech member having a cartridge bullet discharge barrel extending outwardly therefrom, means to support an explosive cartridge within said breech member in aligned

relation to the bore of said barrel, and means to connect said breech member in attached relation to the barrel of an air rifle with the supported cartridge aligned with the bore of the latter, whereby a shot air impelled through the air rifle barrel will strike and fire said cartridge.

2. A cartridge firing attachment for an air rifle comprising a breech member having a cartridge bullet discharge barrel extending outwardly therefrom, means to support an explosive cartridge within said breech member in aligned relation to the bore of said barrel, means for attaching said breech member to the barrel of an air rifle, a hinge connection between said breech member and attaching means, whereby said breech member may be optionally disposed in operative or non-operative relation to the bore of said air rifle barrel, and means to releasably hold said breech member in operative relation to the bore of the air rifle barrel with the supported cartridge aligned with said bore, whereby a shot air impelled through the air rifle barrel will strike and fire said cartridge.

3. A cartridge firing attachment for an air rifle comprising a breech member having a cartridge bullet discharge barrel extending outwardly therefrom, means to support an explosive cartridge within said breech member in aligned relation to the bore of said barrel, and means for attaching said breech member to the barrel of an air rifle including means to optionally dispose the former in operative or non-operative relation to the latter, said breech member, when operatively disposed, being adapted to position the supported cartridge in alignment with the bore of the air rifle barrel, whereby a shot air impelled through the air rifle barrel will strike and fire said cartridge.

4. A cartridge firing attachment for an air rifle comprising a breech member having a cartridge bullet discharge barrel extending outwardly therefrom, a cartridge holding cylinder rotatably mounted in said breech member, rotation of said cylinder being adapted to position a selected contained cartridge in aligned relation to the bore of said barrel, yieldable detent means for holding said cylinder in cartridge aligning relation to the bore of said barrel, and means to connect said breech member in attached relation to the barrel of an air rifle with a positioned cartridge aligned with the bore of the latter, whereby a shot air impelled through the air rifle barrel will strike and fire said cartridge.

5. A cartridge firing attachment for an air rifle comprising a breech member having a cartridge bullet discharge barrel extending outwardly therefrom, a cartridge holding cylinder rotatably mounted in said breech member, rotation of said cylinder being adapted to position a selected contained cartridge in aligned relation to the bore of said barrel, yieldable detent means for holding said cylinder in cartridge aligning relation to the bore of said barrel, and means for attaching said breech member to the barrel of an air rifle including means to optionally dispose the former in operative or non-operative relation to the latter, said breech member, when operatively disposed, being adapted to align a positioned cartridge with the bore of the air rifle barrel, whereby a shot air impelled through the air rifle barrel will strike and fire said cartridge.

6. A cartridge firing attachment for an air rifle comprising a breech member having a cartridge bullet discharge barrel extending outwardly therefrom, a cartridge holding cylinder rotatably

mounted in said breech member, rotation of said cylinder being adapted to position a selected contained cartridge in aligned relation to the bore of said barrel, yieldable detent means for holding said cylinder in cartridge aligned relation to the bore of said barrel, means for attaching said breech member to the barrel of an air rifle, a hinge connection between said breech member and attaching means, whereby said breech member may be optionally disposed in operative or non-operative relation to the bore of said air rifle barrel, and means to releasably hold said breech member in operative relation to the bore of the air rifle barrel with a positioned cartridge aligned with said bore, whereby a shot air impelled through the air rifle barrel will strike and fire said cartridge.

7. A cartridge firing attachment for an air rifle comprising a downwardly open chambered breech member having a cartridge bullet discharge barrel extending outwardly therefrom, the rear wall of said breech member having a touch hole aligned with the bore of said barrel, a cartridge holding cylinder removably mounted in said breech member, a detachable axle pin supported in and between the front and rear walls of said breech member, said axle pin being adapted to rotatably support said cylinder, rotation of said cylinder being adapted to position a selected contained cartridge in aligned relation to and between the bore of said barrel and said touch hole, yieldable detent means for holding said cylinder in cartridge positioning condition, and means to connect said breech member in attached relation to the barrel of an air rifle with its touch hole and a positioned cartridge aligned with the bore of the latter, whereby a shot impelled through the air rifle barrel will strike and fire said cartridge.

8. A cartridge firing attachment for an air rifle comprising a downwardly open chambered breech member having a cartridge bullet discharge barrel extending outwardly therefrom, the rear wall of said breech member having a touch hole aligned with the bore of said barrel, a cartridge holding cylinder removably mounted in said breech member, a detachable axle pin supported in and between the front and rear walls of said breech member, said axle pin being adapted to rotatably support said cylinder, rotation of said cylinder being adapted to position a selected contained cartridge in aligned relation to and between the bore of said barrel and said touch hole, yieldable detent means for holding said cylinder in cartridge positioning condition, and means for attaching said breech member to the barrel of an air rifle including means to optionally dispose the former in operative or non-operative relation to the latter, said breech member, when operatively disposed, being adapted to align its touch hole and a positioned cartridge with the bore of the air rifle, whereby a shot air impelled through the air rifle barrel will strike and fire said cartridge.

9. A cartridge firing attachment for an air rifle comprising a downwardly open chambered breech member having a cartridge bullet discharge barrel extending outwardly therefrom, the rear wall of said breech member having a touch hole aligned with the bore of said barrel, a cartridge holding cylinder removably mounted in said breech member, a detachable axle pin supported in and between the front and rear walls of said breech member, said axle pin being adapted to rotatably support said cylinder, rotation of said cylinder being adapted to position a selected contained cartridge in aligned relation to and between the bore of said barrel and said touch hole, yieldable detent means for holding said cylinder in cartridge positioning condition, and means to connect said breech member in attached relation to the barrel of an air rifle with its touch hole and a positioned cartridge aligned with the bore of the latter, whereby a shot air impelled through the air rifle barrel will strike and fire said cartridge.

a selected contained cartridge in aligned relation to and between the bore of said barrel and said touch hole, yieldable detent means for holding said cylinder in cartridge positioning condition, means for attaching said breech member to the barrel of an air rifle, a hinge connection between said breech member and attaching means, whereby said breech member may be optionally disposed in operative or non-operative relation to

the bore of said air rifle barrel, and means to releasably hold said breech member in operative relation to the bore of the air rifle barrel with its touch hole and a positioned cartridge aligned with said bore, whereby a shot air impelled through the air rifle barrel will strike and fire said cartridge.

RALPH HILLIARD DIXON.
